CLAIM

The ornamental design for a massager, as shown and described.

DESCRIPTION

FIG. 1 is a perspective view of a massager, showing our new design;

FIG. 2 is a top plan view thereof;

FIG. 3 is a side elevational view thereof, the opposite side elevational view being identical thereto; and,

FIG. 4 is a cross-sectional view thereof, taken along line 4—4 of FIG. 3.

1 Claim, 2 Drawing Sheets
